PROCESS OF REFINING GASOLINE PRODUCED BY CRACKING

Claron R. Payne and Donald R. Stevens, Pittsburgh, Pa., assignors to Gulf Refining Company, Pittsburgh, Pa., a corporation of Texas

No Drawing. Application September 19, 1931,
Serial No. 563,886

11 Claims. (Cl. 196—44)

This invention relates to processes of refining petroleum distillates produced by cracking, and particularly to the treatment of such a distillate to reduce its tendency to form and deposit gum in storage receptacles and internal combustion engines. More particularly it relates to the treatment of such a distillate with a small amount of anhydrous aluminum chloride, advantageously between three per cent and about one-half of one per cent, the treatment being conducted at a temperature of about 150° C. to 400° C. and under a pressure of about 1000 to 2000 pounds per square inch, said treatment being continued for a period of from two minutes to twenty minutes.

The major portion of the gasoline and higher boiling distillates, such as kerosene, produced in the United States today is made by cracking, and such distillates so produced are characterized by a tendency to deposit gum in storage vessels. The gasoline deposits gum on the valves and in the cylinders of the engines in which it is used. Similarly such distillates are, in most cases, characterized by undesirably high sulfur content. Common modes of refining these distillates substantially reduce the gum-forming tendency as of the time at which it is treated, but from that moment there is a continuing tendency to form and deposit additional gum and this subsequently formed gum accumulates in substantial quantities in the containers in which the distillates are kept. Gum content is objectionable largely because a considerable portion of the gum which forms subsequent to original treatment deposits on the hot portions of the engine in which it is used and with which it comes in contact, these deposits in the case of gasoline being commonly most marked on the engine valves, on the piston heads, and in the cylinders. Capacity of a gasoline to presently deposit gum is determined by the well known "copper dish test", and ultimate capacity of a gasoline to deposit gum is measured by the similarly well known "oxygen gum test". This ultimate capacity to form gum is commonly referred to as "potential gum".

By our invention we provide a method of refining which removes most of the existing gum content and so reacts with the various constituents of the material under treatment as to greatly reduce the tendency to subsequently generate additional gum, which removes sulfur, and which stabilizes the material as to oxidation and color change. The term "refining" is used herein as a general term descriptive of steps in the preparation of the final product which improve the chemical and physical characteristics of the material

being processed, but do not effect far-going changes in the boiling points of the material being processed. The term "refining", as used herein, is not intended to include cracking processes, hydrogenation, etc.

A pressure still distillate containing a preponderance of gasoline and produced by that type of process which is commercially known as a liquid phase process is most advantageously treated with one-half of one per cent of anhydrous aluminum chloride at a pressure of 1000 pounds per square inch and at a temperature in the neighborhood of 400° C. Higher pressures result in an unnecessarily great loss of material by polymerization and less effective removal of existing gum and preclusion of subsequent gum. A temperature in the neighborhood of 400° C. is the most desirable. Much lower temperatures, while effective in removing the gum, are accompanied by great polymerization losses of the distillate being treated, and about 150° C. is in most cases the minimum. Temperatures much in excess of 400° C. are accompanied by a prohibitive loss in the form of gas. When there is excessive conversion the temperature is lowered but ordinarily not below 150° C. The losses resulting from polymerization are similarly great when the time of treatment substantially exceeds twenty minutes, while a treatment of substantially less than two minutes is ordinarily unproductive of sufficient effect.

The effectiveness of our process is well demonstrated by the treatment of a liquid phase distillate which originally had a gum number of 350 by the well known copper dish method of measuring present tendency to deposit gum, and a gum number of 1100 by the oxygen method commonly used to measure "potential gum". This so-called potential gum is non-existent as gum at the time of making the test but the test is a present measure of the probable ultimate gum formation which will accompany indefinite ageing of the gasoline. On treating the described distillate for two minutes with one-half of one per cent of anhydrous aluminum chloride, at a temperature of 400° C. and under a pressure of 1000 pounds above atmospheric, the former gum number of 350 by the copper dish method was reduced to 62 and the former gum number of 1100 by the oxygen method was reduced to 60; and this improvement in the quality of the product was effected with a polymerization loss of only 8 per cent.

In the treatment of distillates produced by those processes which are commercially known as vapor phase processes we find it desirable to in-

crease the pressure to the neighborhood of 2000 pounds per square inch. The effectiveness of our treatment on such a material is well demonstrated by actual treatments whereby we have reduced the copper dish gum number of a distillate from 540 to 3 and its oxygen gum number from 500 to 10, this result being accomplished with polymerization loss of only 10½ per cent.

We find that our process can be successfully practiced either in an autoclave or in a continuously operating tubular heating apparatus.

Anhydrous zinc chlorid, nickel chlorid and anhydrous ferric chlorid are found to be useful in our process, but we prefer anhydrous aluminum chlorid and we usually employ one-half of one per cent, although we have used as high as three per cent with success, the temperature being controlled to prevent substantial conversion into lower boiling products.

In the ensuing claims the term "cracked distillate" is used to include all petroleum cracking still products having a substantial portion of constituents boiling within kerosene and gasoline boiling point range, whether or not these constituents have yet been separated from constituents of other boiling points. By the term "simple thermal cracking process" we mean a process wherein cracking is pyrolytic, in contrast to that produced by catalytic action. The terms "high pressures" or "high superatmospheric pressures" employed in the claims have the significance which is conventional in this art. High pressures have been defined, for example, as ranging between about 600 and 1500 pounds per square inch. The term "metallic chlorid catalyst" is used to include those metal chlorids which, like aluminum chlorid, have been recognized by the art as useful in removal of undesirable constituents from a given distillate by so-called condensation. These catalysts are characterized by the fact that the contained chlorin is loosely held by the metal in contradistinction to chlorids of strongly basic metals. Among the recognized metallic chlorid catalysts are zinc chlorid, nickel chlorid, ferric chlorid and aluminum chlorid.

What we claim is:

1. In the manufacture of a motor fuel from a cracked gasoline distillate, the refining process which comprises mixing approximately from one-half of one per cent to three per cent by weight of anhydrous aluminum chlorid with the distillate and heating this mixture to approximately 400° C., and maintaining it at that temperature under a pressure of the order of one thousand to two thousand pounds per square inch for a period not substantially greater than twenty minutes; the said distillate being of such type that substantially no conversion takes place during the treatment specified.

2. In the manufacture of a motor fuel from a cracked gasoline distillate, the refining process which comprises mixing approximately one-half of one per cent by weight of anhydrous aluminum chlorid with the distillate and heating this mixture to approximately 400° C., and maintaining it at that temperature under a pressure of the order of one thousand to two thousand pounds per square inch for a period not substantially less than two minutes or substantially greater than twenty minutes; the said distillate being of such type that substantially no conversion takes place during the treatment specified.

3. The process of refining cracked gasoline distillate from a so-called liquid phase cracking process which comprises mixing approximately

from one-half of one per cent to three per cent of anhydrous aluminum chlorid with the distillate and heating this mixture to approximately 400° C. and maintaining it at that temperature under a pressure of the order of one thousand pounds per square inch for a period not substantially greater than twenty minutes; the said distillate being of such type that substantially no conversion takes place during the treatment specified.

4. The process of refining a cracked gasoline distillate from a so-called liquid phase cracking process which comprises mixing approximately from one-half of one per cent to three per cent of anhydrous aluminum chlorid with the distillate and heating this mixture to approximately 400° C. and maintaining it at that temperature under a pressure of the order of one thousand pounds per square inch for a period not substantially less than two minutes or substantially greater than twenty minutes; the said distillate being of such type that substantially no conversion takes place during the treatment specified.

5. The process of refining a cracked gasoline distillate from a so-called vapor phase cracking process which comprises mixing a small amount of anhydrous aluminum chlorid with the distillate and heating the mixture for a short period of the order of two to twenty minutes to temperatures above 150° C. but not exceeding 400° C while maintaining it under a pressure of the order of two thousand pounds per square inch; the said distillate being of such type that substantially no conversion takes place during the treatment specified.

6. The process of refining a cracked gasoline distillate from a so-called vapor phase cracking process which comprises mixing approximately from one-half of one per cent to three per cent of anhydrous aluminum chlorid with the distillate and heating this mixture to approximately 400° C. and maintaining it at that temperature under a pressure of the order of two thousand pounds per square inch for a period not substantially greater than twenty minutes; the said distillate being of such type that substantially no conversion takes place during the treatment specified.

7. The process of refining a cracked gasoline distillate from a so-called vapor phase cracking process which comprises mixing approximately from one-half of one per cent to three per cent of anhydrous aluminum chlorid with the distillate and heating this mixture to approximately 400° C. and maintaining it at that temperature under a pressure of the order of two thousand pounds per square inch for a period not substantially less than two minutes or substantially greater than twenty minutes; the said distillate being of such type that substantially no conversion takes place during the treatment specified.

8. The process of making a motor fuel by refining an unsaturated cracked gasoline distillate derived from a simple thermal cracking process which comprises mixing approximately from one-half of one per cent to three per cent by weight of anhydrous aluminum chlorid with a liquid cracked gasoline distillate and heating this mixture for a short period of the order of two to twenty minutes to temperatures above 150° C. but not substantially exceeding 400° C. while maintaining it in substantially liquid phase under high superatmospheric pressures ranging up to about 2000 pounds per square inch; the said distillate being of such type that substantially no

conversion takes place during the treatment specified.

9. The process of claim 8 in which approximately one-half of one per cent of aluminum chlorid is used.

10. The process of claim 8 in which a temperature around 400° C. is used.

11. In the manufacture of motor fuels from cracked gasoline distillates derived from simple thermal cracking processes, the process which comprises mixing a liquid cracked gasoline

distillate with from one-half to three per cent of a metallic chlorid catalyst, heating the mixture to temperatures above 150° C. but not substantially exceeding 400° C. for a period not substantially exceeding 20 minutes and under high pressure ranging from about 1000 to 2000 pounds per square inch, the said distillate being of such type that substantially no conversion takes place during the treatment specified.
